(57) **CLAIM**

I claim the ornamental design for a hydration reservoir, as shown and described.

DESCRIPTION

FIG. 1 is a perspective view of the first embodiment of a hydration reservoir;

FIG. 2 is a top view of the hydration reservoir of FIG. 1;

FIG. 3 is a bottom view of the hydration reservoir of FIG. 1;

FIG. 4 is a right side view of the hydration reservoir of FIG. 1;

FIG. 5 is a left side view of the hydration reservoir of FIG. 1;

FIG. 6 is a front view of the hydration reservoir of FIG. 1;

FIG. 7 is a rear view of the hydration reservoir of FIG. 1;

FIG. 8 is a perspective view of the second embodiment of a hydration reservoir;

FIG. 9 is a top view of the hydration reservoir of FIG. 8;

FIG. 10 is a bottom view of the hydration reservoir of FIG. 8;

FIG. 11 is a right side view of the hydration reservoir of FIG. 8;

FIG. 12 is a left side view of the hydration reservoir of FIG. 8;

FIG. 13 is a front view of the hydration reservoir of FIG. 8; and,

FIG. 14 is a rear view of the hydration reservoir of FIG. 8.

The broken lines depict portions of the hydration reservoir

and form no part of the claimed design.
